CLAIM

USPC **D15/28**

The ornamental design for an undercarriage track system for mobile earthmoving machine, as shown and described.

(58) **Field of Classification Search**

DESCRIPTION

USPC D15/28, 22-26; 305/196, 106, 119, 202
CPC B62D 55/20; B62D 55/108; B62D 55/12;
B62D 55/14; B62D 55/15

See application file for complete search history.

(56) **References Cited**

FIG. 1 is a top perspective view of an undercarriage track system for mobile earthmoving machine showing our new design;

FIG. 2 is a bottom perspective view thereof;
FIG. 3 is a front view thereof, the rear view being identical;
FIG. 4 is a left side view thereof, the right side view being identical;

FIG. 5 is a top view thereof;
FIG. 6 is a bottom view thereof; and,
FIG. 7 is a partial view thereof.

The broken lines illustrate environmental structure and form no part of the claimed design.

The pairs of closely spaced jagged dot-dashed lines represent indeterminate length and form no part of the claimed design.
